VALÈRE A. FYNNE, OF ST. LOUIS, MISSOURI, ASSIGNOR TO WAGNER ELECTRIC MANUFACTURING COMPANY, OF ST. LOUIS, MISSOURI, A CORPORATION OF MISSOURI.

IGNITION SYSTEM.

1,321,619.

Specification of Letters Patent. Patented Nov. 11, 1919.

Application filed March 7, 1918. Serial No. 221,064.

To all whom it may concern:

Be it known that I, VALÈRE A. FYNNE, a subject of the King of England, residing at the city of St. Louis, State of Missouri, 5 United States of America, have invented a certain new and useful Ignition System, of which the following is such a full, clear, and exact description as will enable any one skilled in the art to which it appertains to 10 make and use the same, reference being had to the accompanying drawings, forming part of this specification.

My invention is more particularly applicable to battery ignition systems for internal combustion engines, operated in conjunction with an electromagnetic starter for the engine.

One of its objects is to improve the operation of the spark coil, and another is to 20 preclude the possibility of the storage battery being drained in case the ignition switch is left closed after the engine has come to rest. A further object is to raise the maximum cranking speed. Other objects and advantages will appear from the 25 following description.

In carrying out my invention, I make use of an auxiliary dynamo connected in series with the storage battery and the spark coil 30 and I provide an electromagnetic switch, which I place in the ignition circuit and control from the terminals of the auxiliary dynamo. I prefer to provide this dynamo with a neutralizing winding.

My invention will be better understood by 35 reference to the accompanying drawings, in which Figure 1 is a diagrammatic representation of one embodiment of my invention for application to an automobile. Fig. 40 2 is a modification thereof.

Referring to the drawings, and particularly to Fig. 1, the storage battery is indicated at 2; 3 and 4 represent respectively the armature, and the field winding of the 45 auxiliary dynamo, which is also provided with a neutralizing winding 35; 5 is the spark coil; 9, the high tension distributor; 7, the interrupter in the low tension ignition circuit; 8, the cam operating the spring 50 controlled interrupter; 14, 15, an automatic

electromagnetic switch in the ignition circuit; 18, a hand-controlled ignition switch; 26, 27, the cranking motor suitably geared to the engine; and 23, 25 is the motor starting switch. The generator usually provided 55 for charging the battery and for carrying at least a part of the load when the engine runs above a certain speed is shown at 32, 33. This generator can be connected in parallel with the battery by means of a 60 switch 34, which is usually of the automatic type.

The auxiliary dynamo 3, 4 is preferably driven from the engine as are the timer cam 8, and the distributor 9. The resistance 65 28, is normally included in the exciting circuit of the auxiliary dynamo. The exciting coil 16, of the electromagnetic switch is arranged to be connected in circuit with the exciting winding 4 of the auxiliary dynamo 70 under certain conditions, while the magnetizing coil 17 of said switch is permanently connected to the terminals of said dynamo. When the engine is at rest, the hand-controlled ignition switch 18 should 75 be in its off position 19; the spring-controlled starting switch 23, 25 should be under the control of its spring and therefore open; the electromagnetic switch 14, 15 should also be under the control of its spring 80 and open. The interrupter 7 may be open or closed according to the position in which the cam 8 has come to rest with reference to the lever of the interrupter, with which it coöperates.

When it is desired to start the engine, it is first necessary to close the ignition switch 18. In so doing, a connection is first made at the point 20 between the negative pole of the battery 2, and one terminal of the coil 16, 90 the other terminal of which is connected to the positive terminal of the battery through the exciting winding 4, of the auxiliary dynamo. This connection energizes the electromagnetic switch 14, 15, causing the 95 contact 12, carried by the movable arm of said switch pivoted at 13, to come in touch with the stationary contact 11. The auxiliary dynamo is at the same time strongly magnetized by the current circulating 100

through its winding 4. A further movement of the switch 18, into its closed position, brings its contact lever into touch with the terminal 21, thus interrupting the circuit through the coils 16 and 4 and interrupting the low tension ignition circuit at points 11, 12. The next operation is to close the starting switch, which in this case is composed of two levers 23, 25, which are mechanically interconnected, but electrically insulated from each other. The lever 23 coming into contact with the terminal 22 completes the circuit of the cranking motor 26, 27 and of the battery 2, thus setting the internal combustion engine, the auxiliary dynamo, the cam and the distributor in motion. Simultaneously, the lever 25 comes into contact with the terminal 24 and connects the battery 2, through the switch 18 and the contact 21 to the coil 16, of the electromagnetic switch and the field winding 4, of the auxiliary dynamo. As a result, the core 15 is energized, the armature 14 attracted, and the ignition circuit closed at the contacts 11, 12. At the same time, an E. M. F. appears at the terminals of the auxiliary dynamo and the connections are so made that this E. M. F. is added to that of the storage battery. The coil 17, being connected to the terminals of the auxiliary dynamo, immediately contributes to the magnetization of 15, and helps to hold the electromagnetic switch closed. The magnetization produced by this coil 17 is in direct proportion to the terminal voltage of the auxiliary dynamo and therefore rises with increasing engine speed.

The starting switch will naturally be held in its closed position until the engine has fired and can operate without the help of the cranking motor. The coil 17 is so proportioned that the magnetization it produces is sufficient to hold the electromagnetic switch closed when the engine runs at any speed equal to or above its lowest operating speed, whether the exciting winding 4 of the auxiliary dynamo is connected to the battery through the coil 16 or the resistance 28.

When the starting switch is closed and the electromagnetic switch is open, then the negative pole of the battery 2 is connected to the exciting winding 4, through the magnetizing coil 16, but when the starting and electromagnetic switches are closed, then the negative pole of the battery is connected to the exciting winding 4, not only through the magnetizing coil 16, but also through the armature 14, the contacts 12, 11, of the electromagnetic switch and the resistance 28.

When the starting switch is released at an engine speed in the neighborhood of the idling speed, then the circuit through the magnetizing coil 16 is interrupted at the point 24 but the electromagnetic switch re-

mains closed because of the voltage at the terminals of the auxiliary dynamo. This voltage is due to the speed of the engine and to the fact that the circuit through the exciting winding 4 is maintained by the electromagnetic switch through the resistance 28. The excitation of the auxiliary dynamo being independent of the position of the interrupter 7, the electromagnetic switch will remain closed as long as the engine speed exceeds a predetermined limit. Should it be desired to cut off the ignition while the engine is running above its idling speed—for instance, while the car coasts down a hill—it is only necessary to open the hand-controlled ignition switch 18. In order to reinstate ignition with the engine running above idling speed, it is sufficient to close the ignition switch 18. As the contact lever passes over point 20, coil 16 is sufficiently energized to close the electromagnetic switch and when the lever comes to dwell on the contact 21, said switch will not open for the reason that the exciting circuit of the auxiliary dynamo will still be closed through the resistance 28. It is preferred to place the contacts 20 and 21 so close together, that the contact lever 18 will make contact with 21 before breaking contact with 20, and vice versa.

In normal operation the starting switch 23, 25 is open and the ignition switch stands on contact 21. In case the engine is stalled, the operator should open the ignition switch, placing it in its off position. If he forgets to do so, then the electromagnetic switch 14, 15 will interrupt the primary of the ignition circuit at points 11, 12, for as soon as the engine speed falls below the idling speed, or as soon as the engine comes to rest, the voltage at the terminals of the auxiliary dynamo is so far reduced as to be insufficient to hold the electromagnetic switch closed through the agency of the magnetizing coil 17. In this way there is never any danger of draining the battery through the spark coil after the engine has come to rest.

The resistance 28 may be omitted. It is, however, useful in that it prevents the coil 16 from being almost short-circuited when the switch 14, 15 closes while 25 is closed, or while the switch 18 stands on point 20. It is further useful in that it makes it easier to so proportion the exciting winding 4 of the auxiliary dynamo as to cause the latter to produce at low engine speeds an E. M. F. of the same order of magnitude as that which it produces at the higher engine speeds with normal excitation. The winding 4 is proportioned to produce over excitation with coil 16 in circuit with it. The resistance of this coil is low. By adjusting the value of the resistance 28 the same winding 4 can be used to produce

normal excitation when operating in series with 28 instead of in series with 16. The advantage of over exciting the auxiliary dynamo during the starting period lies in the 5 fact that the heavy drain on the battery due to the operation of the cranking motor considerably lowers the terminal voltage of said battery and therefore reduces the ignition voltage. Since the auxiliary dynamo 10 is connected to add its E. M. F. to that of the battery, it is clear that the drawback just referred to can to a certain extent be compensated by over exciting said dynamo. When the spark coil is fed from the battery 15 and from an auxiliary dynamo such as 3, 4, connected in series therewith, then the E. M. F. impressed on said spark coil will increase with increasing engine speed and the result obtained will be similar to that secured with 20 a magneto, with the added advantage over the magneto of an energetic spark available even when the engine is at rest.

In Fig. 2, the battery 2 is as before connected in series with the armature 3 of the 25 auxiliary dynamo, with the primary of the spark coil 5, with the interrupter 6, with the contacts 11, 12 of the electromagnetic switch and with the hand-controlled ignition switch 18, 21. The coil 17 is connected to the 30 brushes of the armature 3, and the exciting winding 4 of the auxiliary dynamo is adapted to be connected across the armature 3 in series with the battery 2 and either through the exciting coil 16 of the electromagnetic 35 switch and the ignition switch 18, or through the resistance 28, the contacts 11, 12 of the electromagnetic switch and the ignition switch 18. Whether its circuit is closed through the coil 16, or the resistance 28 de- 40 pends on the position of the spring-controlled switch 29. In its normal position this switch connects one terminal of the exciting winding 4 to the contact 11, through the resistance 28, but it can be moved to contact 45 31 against the spring which controls it, so as to connect one terminal of the winding 4 to the exciting coil 16. The cranking motor 26, 27, the circuit of which is controlled by the switch 23, is also connected in series 50 with the battery 2 and the armature of the auxiliary dynamo 3. It will be understood that the generator 32, 33 shown in Fig. 1 would also be used in connection with the arrangement of Fig. 2, being adapted to be 55 connected to the ignition circuit in parallel with the battery.

In operating the arrangement shown in Fig. 2 on the assumption that the engine is at rest and the switches 23 and 29 are under 60 the control of their respective springs, it is first necessary to close switch 18. Since switch 29 normally stands on point 30 and the electromagnetic switch is normally open, then the closing of switch 18 will have no 65 immediate effect. The next operation is to

close switch 23, thus completing the circuit of the cranking motor and also place switch 29 on point 31. In this position, it completes the circuits of the coils 16 and 4 through the armature 3 and the battery 2. 70 The coil 16 magnetizes the electromagnetic switch and causes same to close the primary ignition circuit at points 11, 12. The cranking motor will start the engine and will cause the auxiliary dynamo, the distributor 75 and the timer to revolve. As soon as the engine has reached a sufficient speed, or a speed equal to, or in excess of its idling speed, then the magnetization produced by coil 17 will, in itself be sufficient to hold the 80 electromagnetic switch closed. As soon as the engine fires, the starting switch may be released; the switch 29 may also be released, either simultaneously with switch 23 or later. As soon as switch 29 is released, the magnetization produced by the coil 16 is reduced 85 to zero, because of the interruption of its circuit at point 31, but the magnetization of the auxiliary dynamo is not interrupted because its circuit is now completed through 90 the resistance 28, the contacts 11, 12 and the ignition switch 18. Should the engine speed fall below a predetermined value, or should the engine stop altogether, then the magnetization produced by coil 17 will be sufficiently 95 reduced to release the electromagnetic switch, thus automatically opening the primary ignition circuit and preventing the battery from being drained, even though the operator should forget to open the hand-controlled ignition switch 18. Should it be desired to cut off the ignition while the engine is running, it is only necessary to open the ignition switch 18. In order to reinstate ignition under such conditions, this switch 18 105 should be closed and the switch 29 momentarily moved to point 31. It is preferable to place the contact points 30 and 31 so close together that the lever 29 may make contact with the one before it breaks contact with the 110 other.

In Fig. 1 the voltage at any time impressed on the terminals of the cranking motor is equal to the voltage then appearing at the terminals of the battery. In Fig. 2, the 115 voltage impressed on the terminals of the cranking motor is always equal to the sum of the voltages of the battery and of the auxiliary dynamo. At the moment of starting, the two arrangements are equivalent, except 120 that the resistance in the circuit of the cranking motor in Fig. 2 is higher than in Fig. 1, but as the engine gathers speed the voltage impressed on the cranking motor in Fig. 2, rises more quickly than that impressed on said motor in Fig. 1, with the result that a higher cranking speed can be reached with the arrangement shown in Fig. 2 for otherwise equal conditions. The arrangement shown in Fig. 2, however, neces- 125 130

sitates an auxiliary dynamo of larger dimensions for the cranking current is many times greater than the ignition current.

The auxiliary dynamo 3, 4, has been provided with a neutralizing winding 35 adapted to produce a magnetization coaxial with that produced by the armature 3, opposed to it in direction and of about the same magnitude. The purpose of this winding is to reduce the impedance of the ignition circuit by eliminating the choke coil effect of the armature 3 of the auxiliary dynamo when traversed by the rapidly pulsating ignition current.

15 Having fully described my invention, what I claim as new and desire to secure by Letters Patent of the United States is:

1. In an ignition system for internal combustion engines, a primary ignition circuit, 20 a controlling switch therefor, a dynamo driven by the engine, and means for holding the controlling switch in closed position, said means being permanently in circuit with the auxiliary dynamo.

25 2. In an ignition system for internal combustion engines, a primary ignition circuit comprising a source of current, an interrupter and a controlling switch, an electromagnet for holding said switch in closed position, means for exciting said magnet from the source of current to close the switch, a dynamo driven by the engine, and means permanently in circuit with the said dynamo for exciting said magnet from said dynamo 30 to hold the switch closed.

3. In an ignition system for internal combustion engines, a primary ignition circuit comprising a source of current and an ignition timer, a switch controlling said circuit, 40 magnetic means for operating said switch, said means comprising two windings, means for connecting one of said windings to the source of current to close the switch, and an auxiliary dynamo driven by the engine and 45 connected in circuit with the other winding.

4. In an ignition system for internal combustion engines, a primary ignition circuit comprising a source of current and an ignition timer, a switch controlling said circuit, 50 an auxiliary dynamo driven by the engine, means for exciting said dynamo from the source of current, and means governed by said dynamo for holding the controlling switch in closed position.

5. In an ignition system for internal combustion engines, a primary ignition circuit comprising a source of current and an ignition timer, a switch controlling said circuit, an auxiliary dynamo driven by the engine, 60 means for exciting said dynamo from the source of current, means governed by said dynamo for holding the controlling switch in closed position, and connections operative when the controlling switch is closed to

maintain the excitation of the auxiliary dynamo. 65

6. In an ignition system for internal combustion engines, a primary ignition circuit comprising a source of current and an ignition timer, a switch controlling said circuit, 70 electromagnetic means for closing said switch, and a single switch for connecting the source of current to the closing means and for opening and closing the ignition circuit. 75

7. In an ignition system for internal combustion engines, a primary ignition circuit comprising a source of current and an ignition timer, a switch controlling said circuit, 80 magnetic means for operating said switch, an auxiliary dynamo provided with an exciting winding, and means for connecting the source of current to said magnetic means and to said dynamo exciting winding. 85

8. In an ignition system for internal combustion engines, a primary ignition circuit comprising a source of current and an ignition timer, a switch controlling said circuit, 90 magnetic means for operating said switch, an auxiliary dynamo provided with an exciting winding, and means for connecting the source of current in series with said magnetic means and said dynamo exciting winding.

9. In an ignition system for internal combustion engines, a primary ignition circuit comprising a source of current and an ignition timer, a switch controlling said circuit, 95 magnetic means for operating said switch, said means comprising two windings, an auxiliary dynamo in circuit with one of said windings and provided with an exciting winding, and means for connecting the second winding of the magnetic means and the exciting winding of the dynamo in circuit 100 with the source of current.

10. In an ignition system for internal combustion engines, a primary ignition circuit, comprising a spark coil, a battery, an auxiliary dynamo driven by the engine and 110 connected to impress a voltage on the spark coil unidirectional with the voltage impressed thereon by the battery, and means for overexciting the auxiliary dynamo when starting the engine. 115

11. In an ignition system for internal combustion engines, a primary ignition circuit, comprising a spark coil, a battery and a controlling switch, electromagnetic means for holding said switch in closed position, 120 an auxiliary dynamo driven by the engine and connected to impress a voltage on the spark coil unidirectional with the voltage impressed thereon by the battery, said dynamo being also in circuit with the electromagnetic means for holding the controlling switch in closed position. 125

12. In an ignition system for internal

combustion engines, a primary ignition circuit, a main dynamo and an auxiliary dynamo, both adapted to supply current to the ignition circuit, a controlling switch for said circuit and means for holding said switch in closed position, said means being governed by the auxiliary dynamo.

13 In an ignition system for internal combustion engines, a primary ignition cir-

cuit comprising a spark coil and a timer, and 10 a dynamo in said circuit, said dynamo being provided with a neutralizing winding adapted to reduce the impedance of the ignition circuit.

In testimony whereof, I have hereunto set 15 my hand and affixed my seal.

VALÈRE A. FYNN. [L.S.]
